ENGINE

Sanford I. Beach, Buffalo, N. Y., assignor of one-half to Lincoln Beach, Miami Beach, Fla.

Application September 22, 1933, Serial No. 699,556

9 Claims. (Cl. 123—50)

This invention relates to engines of the opposed piston type adaptable for operation by steam or as an internal combustion engine and also involves certain features which may be advantageously incorporated in many types of reciprocating compressors.

The primary object of the invention is to provide an improved connecting rod assembly in an engine of this type wherein the power thrust of each piston may be transmitted radially to a single crank pin thereby avoiding the danger of binding at the crank pins such as is liable to occur in the case of dual connecting rods after uneven wear.

In carrying my invention into effect I employ a hollow piston having a second piston reciprocable therein. I take advantage of the fact that the connecting rod of the hollow piston operates in tension and hence permits of a wrist pin assembly such that the thrust may be transmitted through a double pin, one angularly disposed to the other. It thereby becomes a specific object of the invention to teach the construction of this assembly and to provide means by which the assembly may be mounted internally of its piston in such manner that there is no tendency to distort the piston in operation.

Another object of the invention is to provide a valving arrangement in which the inlet and exhaust is controlled by puppet valves, the ports through the hollow piston serving, preferably, only as a passage through which ingress and egress of the gases takes place. I thereby avoid the serious difficulties sometimes encountered because of burnt port holes.

A further object is to provide an improved spark plug placement by which the plug is uncovered for firing and thereafter the plug is isolated from the firing chamber. In this manner I am enabled to retain the better recognized type ignition device without requiring floating wires and other unworkmanlike arrangements such as have been suggested for engines of this type.

Other objects and advantages either directly described or indirectly implied from the favorable arrangement of parts will become hereinafter more fully apparent as reference is had to the accompanying drawings wherein my invention is illustrated by way of example and in which

Figure 1 is a vertical section through an engine taken axially of a cylinder and transversely of the crankshaft to illustrate my invention;

Fig. 2 is a section similar to that shown in Fig. 1 taken longitudinally of the crankshaft;

Fig. 3 is a horizontal section taken along the line 3—3 of Fig. 1;

Figs. 4 and 5 are details of my improved piston sleeve;

Figs. 6 and 7 are enlarged details of the wrist pin assembly of the larger piston shown in Figs. 1 and 2.

More particularly, 1 indicates a cylinder which may be one of a plurality cast in a block. A hollow piston 2 within the cylinder 1 is reciprocable therein and a second piston 3 is reciprocably placed within the hollow cylinder 2. Each of these pistons is connected to a crank shaft 4 in a manner to be hereinafter more fully described.

The cylinder 1 has a walled channel 5 formed therein and puppet valves 6 and 7 control the ingress and egress of fuel and exhaust gases to and from said channel. These valves 6 and 7 are actuated by cams 8 on a crankshaft 9 driven from the crankshaft 4 in the conventional manner.

The hollow piston 2 has a plurality of stepped ports 10 therethrough for establishing communication between its interior and the channel 5. For proper inletting and exhausting these ports 10 must be in communication with the channel 5 during substantially the entire working strokes of the pistons. Thus during the inlet stroke if communication be cut off before the inletting is complete there will be a rarification of the fuel charge and a loss of volumetric efficiency. Also if at the other end of a stroke the ports are not in communication with the channel scavenging of the exhaust gases cannot be completed. It will thus be seen that the ports 10 do not act as slide valves.

Another port 11 is provided in the hollow cylinder 2 which is adapted to uncover the spark plug 12 extending through the side wall of the cylinder 1, at a predetermined period,—that is, when compression is completed. By this arrangement the conventional type plug and wiring connections 13 may be used.

The piston 3 is provided with a wrist pin 14 and a connecting rod 15 for connection to a crank throw 16 of the crank shaft 4. The small end of the connecting rod 15 which attaches to the wrist pin is so constructed that the axis of the rod is offset laterally from the axis of its piston as best seen in Fig. 2.

The inner end portion of the piston 2 is provided with tongues and grooves 17 to receive similar grooves and tongues 18 in a piston sleeve 19. This sleeve, as best seen in Figures 4 and 5 is made of three parts, two of which are almost semi-cylindrical and the third one 24 of which is

- so formed as to act as a wedge to expand and maintain the other two parts in assembly against the tongues and grooves 17. This sleeve 19 constitutes a means for supporting the wrist pin of the piston in such manner as to distribute the loading thereof over the entire base of the piston
- 5 2. A pin 20 spans the sleeve 19 and carries a wrist pin supporting member 21 in which resides a wrist pin 22 upon which is journaled a connecting rod 23 for connection to a second crank throw
- 10 24. The pin 23 is offset from a diameter of the sleeve, as seen in Figure 2 and the wrist pin is on the opposite side of the axis of the cylinder 1 from the connecting rod 15. By this arrangement a single connecting rod is sufficient for each piston 2 and 3. The rod 23 is a tension member and the rod 15 is a compression member during the firing stroke.
- 15 Various modifications may be made without departing from the spirit of my invention and I therefore desire that my protection will be interpreted within the full scope of the appended claims.
- 20 What I claim is:—
- 25 1. In an engine, a cylinder having a hollow piston therein, a second piston reciprocable in said hollow piston, said pistons each having a wrist pin, the two wrist pins in each cylinder being normal to each other, a crankshaft having two
- 30 crank pins for each of said cylinders, a single connecting rod extending from one of said wrist pins to one of said crank pins, and a single connecting rod extending from the other of said wrist pins to the other of said crank pins.
- 35 2. In an engine, a cylinder having a hollow piston therein, a second piston reciprocable in said hollow piston, a crankshaft having two crank throws for each of said cylinders, a connecting rod extending from said hollow piston to one of
- 40 said crank throws and a connecting rod extending from the other of said pistons to the other of said crank throws, each of the connecting rods being offset from the axis of its piston, said connecting rods being connected to wrist pins residing at right angles to each other.
- 45 3. In an engine, a cylinder having a hollow piston therein, a second piston reciprocable in said hollow piston, each of said pistons having a wrist pin therein, said wrist pins each residing within the circumference of its own piston and at right angles to the other, a crank shaft having crank pins, and connecting rods extending from said wrist pins to said crank pins.
- 50 4. In combination, a hollow piston having a wrist pin and a second piston reciprocable therein, a wrist pin for said second piston, a supporting member journaled on said wrist pin spanning said hollow piston for supporting a second wrist pin, a wrist pin journaled on said supporting
- 55 member, a crank shaft having crank pins, and connecting rods extending from said second wrist pin and from the wrist pin in said hollow piston to said crank pins.
- 60 5. In combination, a hollow piston and a second piston reciprocable therein, a wrist pin for said second piston, a wrist pin supporting structure comprising a pin spanning said second piston internally of the circumference thereof at right angles to the first mentioned wrist pin and
- 65 70 a member depending from said pin, a wrist pin

supported by said depending member substantially parallel to said first named wrist pin and residing within the confines of said second piston, a crankshaft having crank pins, and connecting rods connecting the wrist pins with said crank

5

6. In combination, a hollow piston having tongues and grooves in the inner end portion thereof, a second piston reciprocable in said hollow piston and having a wrist pin supported therein, a wrist pin supporting structure comprising a tongue and groove sleeve fitting the grooves and tongues of said hollow piston for support thereby, a pin spanning said sleeve and supported thereby, a wrist pin supporting member depending from said pin, a wrist pin carried by said supporting member, a crankshaft having crank pins, and a connecting rod connecting said wrist pin with said crank pins.

10

7. In combination, a hollow piston having tongues and grooves in the inner end portion thereof, a second piston reciprocable in said hollow piston and having a wrist pin supported therein, a wrist pin supporting structure comprising a split sleeve fitting the grooves and tongues of said hollow piston for support thereby, said split sleeve comprising three segmental portions one of which is of wedge shape to constitute a retaining means for the assembled sleeve, a pin spanning said sleeve and supported thereby, a wrist pin supporting member depending from said pin, a wrist pin journaled in said supporting member, a crankshaft having crank pins, and connecting rods connecting said wrist pins and said crank pins.

35

8. In combination, a cylinder, a hollow piston reciprocable in said cylinder, a second piston reciprocable within said hollow piston, a walled channel formed in said cylinder adjacent said hollow piston approximately midway of the height of the working portion thereof, said hollow piston having a row of ports therethrough for connecting the interior of said cylinder with said channel, said ports being stepped to maintain communication between said channel and the interior of said hollow piston during a substantial portion of the stroke of said piston, two puppet valves in said channel, one of said puppet valves being an inlet valve and the other an outlet valve, and timed means for alternately opening said puppet valves.

45

9. In an engine, a cylinder having a spark plug projecting thereinto along the length thereof, a hollow piston reciprocable in said cylinder, and a second piston within said hollow piston, a walled channel in said cylinder exposed to the side walls of said hollow piston, an inlet and an outlet valve controlling the ingress and egress of fuel charges and exhaust gases respectively thereto, cams for operating said inlet and outlet valves, said hollow piston having a plurality of stepped ports therethrough, the top one of said ports being adapted to uncover said spark plug to the space between the top of said hollow piston and said second piston at a predetermined point in the engine cycle, the remainder of said ports establishing communication between said space and said channel whereby said inlet and outlet valves may control fuel charging and scavenging.
